Patented Oct. 23, 1917.

UNITED STATES PATENT OFFICE.

CHARLES G. BRAY, OF BOWIE, ARIZONA.

ROWING-OAR.

1,244,167.

Specification of Letters Patent.

Patented Oct. 23, 1917.

Application filed May 22, 1917. Serial No. 170,207.

To all whom it may concern:

Be it known that I, CHARLES G. BRAY, a citizen of the United States, residing at Bowie, in the county of Cochise and State 5 of Arizona, have invented certain new and useful Improvements in Rowing-Oars; and I do hereby declare the following to be a full, clear, and exact description of the invention, such as will enable others skilled 10 in the art to which it appertains to make and use the same.

The invention relates to a rowing oar.

The object of the present invention is to improve the construction of rowing oars 15 and to provide a simple, practical and efficient rowing oar of strong, durable and comparatively inexpensive construction adapted to permit the person using the oar to face forward and capable, when the handle sections of the oars are moved forward, of causing the blade sections or portions to move simultaneously in the same direction, whereby a more perfect control of the boat may be obtained.

25 A further object of the invention is to provide a rowing oar of this character which will enable the blade to be readily dipped and raised as required, and which will maintain the handle sections in proper position 30 to be quickly grasped, thereby providing an oar adapted for use in emergencies.

With these and other objects in view, the invention consists in the construction and novel combination of parts hereinafter 35 fully described, illustrated in the accompanying drawing and pointed out in the claims hereto appended; it being understood that various changes in the form, proportion, size and minor details of construction, 40 within the scope of the claims, may be resorted to without departing from the spirit or sacrificing any of the advantages of the invention.

In the drawing:

45 Figure 1 is a plan view of a rowing oar constructed in accordance with this invention.

Fig. 2 is an enlarged horizontal sectional view of the same.

50 Fig. 3 is a central longitudinal sectional view of the oar.

Fig. 4 is a detail perspective view of the oar lock.

55 Like numerals of reference designate corresponding parts in all the figures of the drawing.

In the accompanying drawing, in which is illustrated the preferred embodiment of the invention, the rowing oar comprises in its construction a blade section or member 1 and a handle section or member 2 provided at their adjacent ends with heads 3 and 4 having arcuate series of meshing teeth 5 and 6 and forming gear elements. The heads are provided with attaching 60 shanks 7 and 8, which are secured in longitudinal slots 9 and 10 of the sections or members 1 and 2 by suitable fastening devices 11 and 12. The gear elements are pivotally mounted and maintained in meshing relation by means of tubular pivots 13 and 14, which pass through connecting plates 15. The connecting plates 15 are spaced apart to receive the heads 3 and 4, and the tubular pivots of the joint or connection, formed by the said pivots and the plates, are adapted to receive pivots 16 and 17 of a row lock. The row lock is composed of a central longitudinal pintle 18 and arms 19 and 20 formed by bending the 65 metal of which the row lock is constructed laterally in opposite directions and then longitudinally and then upwardly to provide the pivots 16 and 17. The arms 19 and 20 are approximately L-shaped and the pivots 70 16 and 17 extend upwardly from the arms at opposite sides of the oar lock. The pintle 18 is mounted in eyes 21, which are suitably secured to the gunwale of a boat 22. The gunwale of the boat is preferably provided with a rounded transversely convex 75 upper edge or face 23.

The oar is adapted to rock on the pintle 18 to dip and elevate the blade, and when the handle portion or section 2 is moved 95 forwardly, the blade will move in the same direction, and when the said handle portion or section is moved rearwardly, the blade will be carried in the same direction. This will enable the rower to face the front 100 of the boat, which can thereby be handled with greater accuracy and certainty in rowing, guiding, landing and the like, and many feats in sport and under other conditions may be performed with the rowing oar. 105 Also in rescuing a person from drowning, the oarsman will not only be able to reach a person with greater rapidity and certainty, but will be in a better position for rescuing a person.

110 The blade section or member and the handle section or member may be con-

structed of any suitable material to adapt the oar for various kinds of row boats and the like.

What is claimed is:

- 5 1. The combination with a boat having spaced bearings, of an oar lock consisting of a pintle extending through the bearings, pivots connected with the pintle at the outer sides of the said bearings to retain the pintle therein, and an oar composed of blade and handle sections mounted on the said pivots and provided with teeth arranged in meshing relation.
- 10 2. A rowing oar comprising blade and handle sections provided with heads hav-

ing teeth, connecting means having pivots for the said heads and provided thereat with openings, and an oar lock consisting of a pintle, and substantially shaded arms connected with the ends of the pintle 20 and having projecting terminal pivots arranged in the said openings, and bearings receiving the said pintle.

In testimony whereof I affix my signature in the presence of two witnesses.

CHARLES G. BRAY.

Witnesses:

ELSIE M. HOWELL,
ESTELLE MARIE JAQUE.
